UNITED STATES PATENT OFFICE.

ALBERT J. FORD, OF NEW YORK, N. Y., ASSIGNOR TO THE FUCHS & LANG MANUFACTURING COMPANY, A CORPORATION OF NEW YORK.

BRONZING-MACHINE.

1,107,773.

Specification of Letters Patent. Patented Aug. 18, 1914.

Application filed December 6, 1911. Serial No. 664,170.

To all whom it may concern:

Be it known that I, ALBERT J. FORD, a citizen of the United States, residing in the borough of Manhattan, city of New York, in the county of New York and State of New York, have invented certain new and useful Improvements in Bronzing-Machines, of which the following is a specification, reference being had therein to the accompanying drawings, forming part thereof.

My invention relates to machines for applying bronze powders or similar materials to the surface of paper or other materials in the process of printing the same.

In using bronzing machines it is customary to first print with a size or other suitable adhesive in the pattern to be bronzed and thereafter to pass the sheets through the bronzing machine, which applies bronzing powder to the entire face of the sheet. The powder clings to the size, and the surplus bronze is removed by a dusting operation in the bronzing machine.

It has been found in practice that the paper or other material and any ink thereon from other printing operations, are frequently tacky or sticky, with the result that the bronze powder adheres not only to the parts that have been printed in size for the purpose of retaining the bronze powder, but also to other parts of the sheet, and that it is not removed from these other parts of the sheet by the dusting appliances, so that it continues to adhere to the sheet and seriously mars the product, and is in many respects highly objectionable. This difficulty has heretofore been met by performing as a separate operation, in a separate machine, the application to the sheet of a drying powder, such as magnesia or talcum. This separate operation has been performed preliminarily to the two steps of the bronzing operation, one the printing in size or adhesive and the other the application of bronze powder and removal of surplus bronze.

My invention aims to dispense altogether with the separate machine for applying the drying powder, and with the separate preliminary operation of applying such powder. I have discovered that if the applica-

tion of the drying powder follows the application of the bronze powder, the drying powder is effective in removing the stickiness of the sheet and in loosening any bronze which has adhered to sticky portions of the sheet other than the portions printed in size, and is also effective in removing any sticky condition of the bronzed portions of the sheet, where the size is properly covered with bronze adhering thereto, and that in thus removing the stickiness it does not impair the adhesiveness of the bronze to the size.

My invention includes in a bronzing machine, means for applying a drying powder to a sheet after the bronzing powder has been applied thereto. More specifically my invention includes means for applying a drying powder after the bronze powder has been applied and the surface of the sheet has been subjected to a dusting operation, and more specifically my invention includes means for applying a drying powder at an intermediate point of the dusting operation to be followed by a thorough final dusting of the sheet.

My invention also includes novel and convenient means for feeding the bronze powder to the bronze applying means and includes means for withdrawing surplus powder from the chamber containing the bronzing devices and delivering it to the feeding device, whereby the bronze powder is automatically returned and dried by the presence of the drying powder.

Other features of my invention and objects and advantages thereof will appear from the following particular description of means embodying my invention.

I shall now describe the bronzing machine illustrated in the accompanying drawings and embodying my invention, and shall thereafter point out my invention in claims.

Figure 1 is a rear side elevation of the bronzing machine. Fig. 2 is a vertical central section of the same. Fig. 3 is an enlarged elevation of a portion of the machine as viewed from the right in Figs. 1 and 2, and illustrates particularly the means for applying the drying powder. Fig. 4 is an elevation to the same scale as Fig. 3, of what

is shown in Fig. 3 as viewed from the right. Fig. 5 is an enlarged detail in side elevation of the feeding mechanism. Fig. 6 is a central vertical section of the same on a plane extending longitudinally of the bronzing machine. Fig. 7 is partly a front elevation and partly a section of the same, with parts broken away. Fig. 8 is a detail in front elevation of one of the units of the intermittent or stop gearing.

My invention is shown as embodied in a bronzing machine of a type familiar to those skilled in the art, machines of this type being illustrated, for example, in the 15 patents to Emmerich and Vonderlehr, Nos. 613,412 and 613,857. The machine includes the usual sheet carrier, consisting of a cylinder 1 provided with grippers 2. The bronze powder is applied to the sheet by a 20 feeding device hereinafter to be described, and is rubbed in and burnished by the usual buffing pads 4 and a burnishing roll 5, covered with suitable material, such as plush. After the paper passes the burnishing roll, 25 it is dusted, as is common in such machines, by a dusting roll 6, consisting of cotton disks, which is rapidly rotated by suitable gearing. In some machines this completes the dusting operation, there being one or 30 several of the dusting rolls 6, as desired, the grippers then being released and the paper discharged from the cylinder by suitable mechanism. In other machines a further 35 dusting operation is performed upon the reverse side of the paper, as in the machine disclosed in my Patent No. 1,008,129 of November 7, 1911. In the machine shown, the dusting operation effected by the roll 6 is only a preliminary dusting, after which the 40 drying powder is applied, and then there is a final dusting of the paper on both sides.

A magnesia fountain or receptacle 7 for the drying powder, located below and at the left of the cylinder 1, is open at the side of 45 the top adjacent to the cylinder, and at the other side of the top is provided with a lid 8. Within the magnesia fountain are two plush-covered rolls, an upper powder-applying roll 9 adjacent to and shown as in 50 contact with the cylinder 1 and a lower powder-distributing roll 10 in contact with the powder-applying roll 9 and in proximity to the transversely rounded bottom of the magnesia fountain 7.

55 The powder-applying roll 9 is rotated in the same direction of rotation as the cylinder 1 so that the adjacent or contacting portions of the roll 9 and the cylinder 1 move in opposite directions. As viewed in Figs. 60 1 and 2 of the drawings, the rotation of the powder-applying roll 9 and of the cylinder 1 would be counter-clockwise, and as viewed in Fig. 4 these rotations would be clockwise, as is indicated in each instance by the 65 arrows. The powder-applying roll 9 ro-

tates in contact with and with some pressure against a scraper 11, fixed along the adjacent upper edge of the magnesia fountain 7. The powder-distributing roll 10 rotates in an opposite direction to the powder-applying roll 9, so that the contacting surfaces roll together.

At one end the rolls 9 and 10 are geared together by spur gears 12 the lower one of which is rotated by a pinion 13 carried by the inner end of a stub shaft 14 which is rotated by a train of reducing gears 15, 16, 17 from the large gear wheel 18 rotating with the cylinder 1.

Any suitable drying powder may be used, 80 for examples, magnesia, talcum, soapstone, French chalk, powdered mica.

After the paper leaves the powder-applying roll 9 it is again dusted by a pair of dusting rolls 19, similar to the dusting roll 6, which perform a final dusting operation on the bronzed face of the sheet. Because of the fact that the tack or stickiness has been removed from the ink and the paper by the magnesia or other drying powder, as hereinbefore explained, this last dusting operation will remove all of the remaining superfluous bronze powder from the face of the sheet. The sheet next passes under a felt-covered friction or drawing roll 20, 85 after which it is released from the grippers 2 and is grasped by other grippers 21 carried by a smaller auxiliary cylinder 22 to which the paper is transferred with the reverse side out. The exposed reverse side of 90 the sheet is now dusted by a pair of dusting rolls 23. The sheet then passes under a rubber-covered delivery roll 24 and is finally released by the grippers 21 and is discharged from the auxiliary cylinder 22 by 95 the usual cords 25 forming part of a usual delivery mechanism.

The entire bronzing, drying and dusting devices are inclosed in a casing 26 which retains the surplus bronzing and drying powders and from which these powders are removed by an exhausting device.

The illustrated exhausting device consists of a rotary fan 27 communicating with a delivery pipe 28, through which the air and powder which are exhausted from the casing 26 are delivered to a collector, preferably a cyclone separator 29 of well known construction, located above and opening into the feeding device. This feeding device, 115 which is illustrated in detail in Figs. 5, 6 and 7, will now be described.

The feeding device includes two receptacles or fountains, the distributing fountain 30, into the top of which the collector 125 opens, and the feed fountain 31 below the distributing fountain. At the bottom of the feed fountain 31 is a usual bronze powder-applying device, consisting of a plush roller 32 intermittently actuated in timed relation 130

with the operation of the sheet-feeding mechanism by the usual ratchet and pawl device operated by a cam 32^a on the cylinder shaft and a connecting rod 32^b operatively connected to the cam and pawl in the usual way. The powder is intermittently fed from the distributing fountain to the feed fountain through an intermittent feed device about to be described.

10 The collector opens centrally into the distributing fountain 30, and the bronze powder consequently tends to accumulate or pile up in the center of the distributing fountain, and in order that the powder may be fed 15 equally along the bronze-applying roller 32, it is desirable to distribute the powder evenly in the distributing fountain. To effect this even distribution, a distributing screw 33 is provided in the fountain extending transversely of the machine. The distributing screw has a volute feed flange 34 extending from the center outwardly and oppositely to the ends, whereby the powder as it falls into the distributing fountain is 20 fed equally in both directions and is evenly distributed in the fountain as the screw is rotated.

The distributing fountain 30 has a bottom which is substantially V-shaped or downwardly sloping toward the center, the apex extending longitudinally of the fountain and transversely of the machine. This bottom has an opening at one side of the apex extending the full length of the fountain 35 and providing communication between the distributing fountain 30 and the feed fountain 31. To control this opening, an intermittent feed device 35 is employed, comprising an intermittently rotated hollow tube 40 having a slotted opening extending the full length of the tube and adapted to register in one position of rotation of the feed tube with the opening in the bottom of the distributing fountain. The tube 35 is so located that its cylindrical periphery forms a 45 closure for the communicating opening between the two fountains, and it operates in its rotation to receive bronze powder from the distributing chamber when the slotted 50 opening registers with the opening in the bottom of the distributing chamber, and to dump the powder into the feed fountain when the slotted opening is down.

The bronze-applying roll 32 is rotated in 55 a clockwise direction as viewed in Fig. 6, and rotates in contact with a plate 36 which serves as a scraper. To hold the bottom of the feed fountain tightly against the roll 32 on the side opposite the scraper 36 and 60 prevent any bronze from escaping by that way into the casing 26, the bottom is yieldable and a bell crank lever 37 is pivoted to bear with one arm against the bottom and a set screw 38 screws into the casing and is 65 arranged to bear against the other arm of

the lever and control the adjustment of the bottom of the fountain and press it toward the roll 32. To lower the air pressure in the feeding device, communication is provided between the distributing fountain 30 and the 70 chamber through a passageway 39 at the side of the feeding device, the passageway leading from the middle of the distributing fountain to the chamber containing the bronzing devices.

75 Rotation is imparted to the distributing screw 33 from the large gear 18 on the cylinder shaft, through a train of reducing gears comprising a gear wheel 40 fixed on one end of the screw shaft and rotated by a 80 pinion 41 mounted on a stub shaft 42 on the side of the casing of the feeding device, and secured to a gear wheel 43 mounted on the stub shaft 42 and meshing with the gear 18.

85 The intermittent feed device 35 is intermittently rotated from the shaft of the distributing screw 33 through intermittent or stop reducing gearing, which will now be described. Each unit of this gearing comprises a driving wheel 44 having a single 90 tooth-engaging notch, and a co-operating driven pinion having alternately full width and half width teeth. One of these units is shown in detail in Fig. 8 (see also Figs. 5 and 7). Each of the driven pinions 45 has 95 alternate full-width and half-width teeth, four of each. On each side of the tooth-engaging notch is a laterally projecting pin or lug 46. Each intermittently driven pinion 45 in locked position rides with two adjacent full-width teeth on the periphery of its driving wheel 44 and with the intermediate half-width tooth projecting along the side in the path of the lugs 46. As the intermittent driving wheel rotates, the lug 46 in advance engages the narrow tooth and rotates the intermittently driven pinion and the rear full-width tooth rolls down between the lugs 46 and into the tooth-engaging notch. The further rotation of the driving 100 wheel carries that full-width tooth up on the periphery and the one behind it now also rests on the periphery and the intermediate narrow tooth is in the path of the lugs 46, and the two full-width teeth lock the intermittently driven pinion against further actuation until the advance lug of the driving wheel in its rotation strikes the narrow tooth in its path. This operation is repeated 105 once for every rotation of the intermittent driving wheel. In the illustrated machine, four of these units are employed. The first intermittent driving wheel 44 of the train is fixed on the end of the distributing screw 33 opposite the gear wheel 40, and the last 110 driven pinion 45 is fixed on the end of the shaft of the intermittent feed device 35. It is apparent that a considerable reduction is 115 thereby conveniently obtained, and that the intermittent feed device is rotated thereby 120

125 130 135

in a counter-clockwise direction, as viewed in Fig. 6, and that each intermittent actuation of the intermittent feed device is 90 degrees. The parts are so arranged that the intermittent feed device in three positions completely closes the opening in the bottom of the distributing fountain 30, and in its fourth or filling position the rear edge of the slotted opening is moved past the apex 10 of the V-shaped bottom, and since the movement to the successive positions is quick, there is at no time direct communication between the distributing and main fountains. It is apparent that the intermittent feed 15 device 35 serves also as a measuring device for the bronze powder supplied to the feed fountain 31. By my improved feed mechanism, therefore, the surplus bronze powder is returned in a dry condition to the distributing fountain ready to be immediately re-used, and the bronze is properly distributed and is automatically fed at regular intervals to the bronze-applying device without the necessity of any attention on the 20 part of the operator. The drying powder mingles as a very fine dust with the bronze dust in the chamber and in the exhaust devices and may unobjectionably escape with the air delivered from the cyclone separator. 25 This dust is so exceedingly fine that it is difficult to determine what becomes of it. Apparently to some extent it continues to mingle with the bronze dust throughout the machine, as its drying function is noticeable 30 throughout the machine.

Various modifications may be made in the construction shown in the drawings and above particularly described within the principle and scope of my invention.

43 I claim:

1. A bronzing machine comprising a sheet carrier, means for applying bronze powder to the sheet, and means for applying a drying powder to the sheet after the bronze powder has been applied and while the sheet 45 is in the bronzing machine.

2. A bronzing machine comprising a sheet carrier, means for applying bronze powder to the sheet, means for dusting the bronzed 50 surface, and means for immediately thereafter applying a drying powder to the dusted surface while the sheet is in the bronzing machine.

3. In a bronzing machine, the combination, 55 with a sheet carrier, bronze applying means and a chamber containing the same, of means in the chamber for applying a drying powder to the sheet, a bronze receptacle, an exhaust device adapted to withdraw air and 60 dust from the chamber and deliver the bronze thus withdrawn to the bronze receptacle, and means for delivering bronze from the bronze receptacle to the bronze applying means.

65 4. In a bronzing machine, in combination

with a bronze receptacle and with a sheet carrier, means for evenly distributing the bronze in the receptacle, means for feeding bronze from the receptacle to the sheet carrier comprising intermittently operated 70 bronze-applying means adjacent to the sheet carrier, and an intermittent feed device operative to feed bronze at intervals from the receptacle to the bronze-applying means.

5. In a bronzing machine, in combination 75 with a bronze receptacle and with a sheet carrier, a rotative screw disposed in the receptacle transversely of the machine for evenly distributing the bronze in the receptacle, means for feeding bronze from the receptacle to the sheet carrier comprising bronze-applying means adjacent to the sheet carrier, and an intermittent feed device operative to feed bronze at intervals from the receptacle to the bronze-applying means. 80

6. In a bronzing machine, in combination 85 with a sheet carrier, a bronze distributing receptacle, means for evenly distributing the bronze in the receptacle, bronze-applying means adjacent to the sheet carrier, and an intermittent feed device arranged as a closure for the receptacle and comprising a rotative container adapted in one position of its rotation to receive bronze from the receptacle and in another position of its rotation 90 to feed the bronze thus received to the bronze-applying means.

7. In a bronzing machine, in combination 95 with a sheet carrier, a bronze distributing receptacle, a rotative screw disposed in the 100 receptacle transversely of the machine for evenly distributing the bronze in the receptacle, bronze-applying means adjacent to the sheet carrier, and an intermittent feed device arranged as a closure for the receptacle and 105 comprising a rotative container adapted in one position of its rotation to receive bronze from the receptacle and in another position of its rotation to feed the bronze thus received to the bronze-applying means. 110

8. In a bronzing machine, the combination 115 with a sheet carrier, bronze applying means and a chamber containing the same, of a bronze receptacle, an exhaust device adapted to withdraw air and dust from the chamber 120 and deliver the bronze thus withdrawn to the bronze receptacle, means for evenly distributing the bronze in the receptacle, and an intermittent feed device arranged as a closure for the bronze receptacle and operative to feed bronze at intervals from the receptacle to the bronze-applying means. 125

9. In a bronzing machine, the combination, 130 with a sheet carrier, bronze-applying means and a chamber containing the same, of means in the chamber for applying a drying powder to the sheet, a bronze receptacle, an exhaust device adapted to withdraw air and dust from the chamber and deliver the bronze thus withdrawn to the bronze receptacle.

tacle, means for evenly distributing the bronze in the receptacle, and an intermittent feed device arranged as a closure for the bronze receptacle and operative to feed 5 bronze at intervals from the receptacle to the bronze-applying means.

In testimony whereof I have affixed my signature in presence of two witnesses.

ALBERT J. FORD.
